ABSTRACT OF THE DISCLOSURE

The present invention concerns a double-layer winding device, especially for textile webs, which operates in conformity with the duplex winding with two hank rollers of changing direction of rotation for storing the goods which are withdrawn in a continuous uninterrupted process.

The invention is characterized in that one of the two hank rollers is rotatably journaled in a stationary bearing whereas the second hank roller is tiltable about the first hank roller in steps of 180° while being tilted in this way in an intermittent manner. The tiltable or second hank roller is frictionally driven by the first hank roller and the goods are wound onto the respective empty hank roller while forming a fold at the start of the last-mentioned winding-up operation.

The invention relates to a double winder for treating textile webs in which by alternately loading two rotatable hank rollers, the textile webs can be stored for a longer period of time in a container although the webs are being withdrawn from the container in a continuous uninterrupted process.

It is an object of the present invention to provide a double winder of this type which is materially improved in structural and functional respect.

It is another object of this invention to provide a double winder which will considerably simplify the driving arrangement therefor.

These and other objects and advantages of the invention will appear more clearly from the following specification in connection with the accompanying drawings, in which:

FIG. 1 is a diagrammatic illustration of a side view of a double winder with all important mechanical devices in connection with a pressure bleaching container indicated in dash lines.

FIGS. 2 to 9 diametrically illustrate the various phases during the alternate loading and unloading of the hank rollers.

The above outlined objects have been realized according to the present invention by arranging the journal for one of the two rollers stationarily and providing the thus journaled roller with a drive, whereas the second roller is adapted to be moved in steps over 180° relative to said first roller but always in the same direction in a counterclockwise sense. This movement is effected intermittently, and the second roller is rotated by the first roller by friction. Furthermore, with each intermittent movement of the second roller, the winding direction of the goods is reversed and the goods are by means of pivotable compressed air nozzles or in view of the adhesion by moisture pressed into the gap between the two rollers whereby the respective empty roller is rotated.

The advantage of this device consists in that in view of the rotation of the movable hank roller by friction or by a reduced distance between said rollers, the driving mechanism will be greatly simplified, while the overall size of the device will be considerably reduced. Furthermore, the bend or fold at the start of the two-layer wind-

2

ing will be effected without mechanical means, and due to the mutual turning of the rollers while they are pressed against each other under a substantially constant pressure, the goods will be in firmer engagement with the rollers.

Referring now to the drawings in detail, roller 1 is mounted on a shaft 3a journaled in a stationarily arranged bearing 3, whereas roller 2 is journaled in a radially movable bearing 4 and is adapted to be moved in the direction of the arrows A (FIGS. 2-9) always in counterclockwise direction and, more specifically, each time by 180°. By a correspondingly strong shaft 3a, roller 1 is alternately rotated in clockwise and counterclockwise direction by a wheel 1a and a reversible motor 18. Also arranged on shaft 3a are two strong arms 5, and 5a which on one side support guiding means 6 for the displacement of bearing 4 when the wound up material increases whereas the other arm carries a compressed air operable cylinder piston system 7. Said cylinder piston system is adapted by means of a link system 7a to pull the two bearings 4 of the movable roller 2 under constant pressure against the driving roller 1. The pivotal movement of the two arms 5, 5a is effected by two gears 8a and 8 by means of motor 9 and transmission means 9a. The start of the movement for the counterclockwise rotation of the arms 5 and 5a and the starting of the change of the driving sense of the main roller 1 is brought about by closing limit switch 20 by a nose 21 of the link system 7a and by contact 20a when rollers 1 and 2 are fully wound. The electrical wiring of the control circuit is not shown inasmuch as circuits of such type are well known in the art of reversible motors. The arrangement also comprises a nozzle pipe 12 which is arranged above the driving roller and is pivotable at 14 by means of a lever 13. In view of the fact that the two rollers roll upon each other, not only a compact structure is obtained but also the advantage that the winder can be built into closed processing chambers, especially into those which are under pressure, whereby the double winder will act as a storing device with a considerable increase in the staying time during which the goods stay in the container in a manner similar to J-boxes.

Thus it is possible to reduce the working pressure which in turn considerably reduces the costs for the pressure container. This possibility is illustrated in FIG. 1 by indicating a pressure container 16 in dash lines. With this arrangement, on the right-hand side of the winder, there is provided a compensator 15 which assures the tensioning of the web when roller 2 is shifting in the other direction. With installations of this type, the feeding and withdrawal of the goods 10 is effected through pressure-tight bodies 17 which are well known in the art and, therefore, are illustrated diagrammatically only in FIG. 1. When installing a double winder according to the present invention in a textile treating container, the driving gears 8 together with the drive for the roller 1 are advantageously arranged outside the container.

Operation

The operation of the arrangement is as follows: The goods 10 passing into the arrangement from the top over feeding rollers F have their start 11 passed between and through the two rollers 1 and 2 and wound around main roller 1 in a single layer. Thereupon, the drive for shaft 3a is made effective so that said shaft turns around in clockwise direction (arrow B) as shown in FIG. 2, until half of the total winding diameter has been obtained. After this has been accomplished, the pivotable roller 2 is shifted in counterclockwise direction (arrow A, FIGURE 2) to its left-hand position, as shown in FIG. 3. Furthermore, the nozzle tube 12 is brought into the posi-

tion shown in FIG. 4 in which it is at the level of the roller bite between the two rollers 1 and 2 whereupon the web of goods is by means of compressed air leaving said nozzle 12, pressed into said bite. When at this time, the direction of rotation of main roller 2 is changed, the goods will be wound upon roller 2 in a double layer. This depositing of the goods in a double layer is due to the fact that on one hand the oncoming goods are deposited on roller 2, and on the other hand the goods previously deposited on roller 1 are likewise deposited on roller 2. After the winding diameter of roller 2 has reached its desired maximum or "full" value, the main roller 1 is empty and the start section 11 of the goods which is now on top or on the outside of pivotable roller 2 is thereupon withdrawn, as indicated by the dash-line 15a (FIG. 1) through compensator or cushioning system 15, while at the same time the full hank of roller 2 is shifted by 180° into its right-hand position, as shown in FIG. 6. Nozzle tube 12 is then again moved into the roller gap, and the oncoming goods are wound upon main roller 1. As soon as main roller 1 is full (FIG. 8), the empty roller (FIG. 2) again is shifted by 180° in counterclockwise direction so as to reach its left-hand position shown in FIG. 9. Thereupon nozzle tube 12 is again moved into the bite or gap between rollers 1 and 2 and the cycle is repeated, as mentioned above in connection with FIG. 7, and the goods are again wound on roller 2 as shown in FIG. 5.

Inasmuch as the oncoming goods are impregnated with a bleaching or other liquor, it will be appreciated that when reversing the direction of rotation, the goods will by themselves adhere to the respective empty roller and form the bending fold so that in most fields of application, the arrangement of a nozzle tube will not be necessary.

It is, of course, to be understood that the present invention is, by no means, limited to the particular arrangement referred to above and illustrated in the drawings, but also comprises any modifications within the scope of the appended claims. Thus it is also possible to drive the individual rollers by means of shafts coupled through the intervention of differential transmissions in a manner similar to that employed in connection with jigs. It is merely important that one roller has its bearing stationarily arranged while the second roller moves in intermittent steps about the first roller in the same direction.

What I claim is:

1. A double layer winding arrangement, especially for textile material, which includes: first roller means adapted to receive the textile material to be wound thereon, shaft means supporting said first roller means and rotatably connected thereto, normally stationary bearing means rotatably supporting said shaft means, reversible motor means drivingly connected to said shaft means for selectively rotating said shaft means and thereby said roller means in either direction, second roller means adapted to receive textile material to be wound thereon and being frictionally drivable by said first roller means, supporting means rotatable about said shaft means in steps of 180° and supporting said second roller means, control means operatively connected to said supporting means for stepwise rotating the same by 180° and means for holding said second roller means at a desired variable distance with regard to the axis of rotation of said first roller means.

2. An arrangement according to claim 1, in which said first and second roller means define a bite therebetween, and which includes air-blowing means movable selectively to and from the bite between said first and second roller means and operable to press textile material conveyed to said bite into the latter.

5 3. A double layer winding arrangement, especially for textile material, which includes: first roller means adapted to receive textile material to be wound thereon, shaft means supporting said first roller means and rotatably connected thereto, normally stationary bearing means rotatably supporting said shaft means, reversible motor means drivingly connected to said shaft means for selectively rotating said shaft means and thereby said roller means in either direction, second roller means adapted to receive textile material to be wound thereon and being frictionally drivable by said first roller means, supporting means rotatably supported by said shaft means and supporting said second roller means while being rotatable about said shaft means in steps of 180°, control means operatively connected to said supporting means for stepwise rotating the same by 180° and means for holding said second roller means at a desired variable distance with regard to the axis of rotation of said first roller means.

10 4. An arrangement according to claim 3, in which said supporting means is formed by arm means pivotally connected to said shaft means.

15 5. A double layer winding arrangement, especially for textile material, which includes: first roller means adapted to receive textile material to be wound thereon, shaft means supporting said first roller means and rotatably connected thereto, normally stationary bearing means rotatably supporting said shaft means, reversible motor means drivingly connected to said shaft means for selectively rotating said shaft means and thereby said roller means in either direction, second roller means adapted to receive textile material to be wound thereon and being frictionally drivable by said first roller means, supporting means rotatably supported by said shaft means for rotation about said shaft means in steps of 180° and supporting said second roller means, control means operatively connected to said supporting means for stepwise rotating the same by 180° and means operatively connected to said second roller means and continuously urging the same toward said first roller means so as to cause said first roller means frictionally to drive said second roller means through textile material passing therebetween.

20 6. An arrangement according to claim 1, which includes compensating means for maintaining under tension the textile material being withdrawn from either one of said roller means during a rotation of said second roller means about said first roller means and during changes in the winding diameter during such rotation.

25 7. An arrangement according to claim 1, which includes housing means surrounding said first and second roller means and said supporting means therefor in a substantially pressure-tight manner while permitting the passage of textile material into and out of said housing means.
